(57) **CLAIM**

The ornamental design for an electronic cable, as shown and described.

DESCRIPTION

FIG. 1 is a front perspective view of an electronic cable;

FIG. 2 is a left side perspective view thereof;

FIG. 3 is a front elevation view thereof;

FIG. 4 is a rear elevation view thereof;

FIG. 5 is a left side view thereof;

FIG. 6 is a right side view thereof;

FIG. 7 is a top view thereof; and,

FIG. 8 is a bottom view thereof.

In the drawings, the broken lines are for the purpose of illustrating portions of the electronic cable that forms no part of the claimed design.
